UNITED STATES PATENT OFFICE.

JOHANN HOFMANN, OF WEST COVINGTON, KENTUCKY, ASSIGNOR TO
ERNST H. HUENEFELD, OF CINCINNATI, OHIO.

MECHANICAL MOVEMENT.

No. 839,146.

Specification of Letters Patent.

Patented Dec. 25, 1906.

Application filed February 13, 1903. Serial No. 143,255.

To all whom it may concern:

Be it known that I, JOHANN HOFMANN, a resident of West Covington, in the county of Kenton and State of Kentucky, have invented 5 certain new and useful Improvements in Mechanical Movements; and I do hereby declare the following to be a full, clear, and exact description of the invention, such as will enable others skilled in the art to which it app pertains to make and use the same.

My invention relates to an improved mechanical movement, the object of the invention being to provide improved mechanism in which continuous rotary motion in either 15 direction is converted into alternating rotary motion; and my improvements are particularly adapted for use on washing-machines and the like and is of simple construction and perfect in operation.

With this object in view the invention consists in certain novel features of construction and combinations and arrangement of parts, as will be more fully hereinafter described, and pointed out in the claim.

In the accompanying drawings, Figure 1 is a view in side elevation, illustrating my improvements. Fig. 2 is a view in longitudinal section. Fig. 3 is a detail view of one of the segmental gears 13, and Figs. 4 and 5 are views illustrating the clutch mechanism.

1 represents the cover of a washing-machine or other suitable support, to which the base-plate 2 of my improved frame 3 is secured in any approved manner. Vertical standards 4 are made integral with base 2 and have bearings 5 at their upper ends, preferably removably secured to the standards 4 by screws, as shown, for convenience in assembling the parts. In these bearings 5 a drive-shaft 6 is mounted and has secured on one end, which projects beyond a standard 4, a collar 7, and a drive-gear 8 is secured on the drive-shaft on the opposite side of said standard, said collar and gear serving to hold the shaft against longitudinal movement. This drive-gear 8 receives motion from a smaller gear 9, fixed to an operating-shaft 10, supported in a bracket 11 at one end of base-plate 2 and in a bearing in a standard 4 and 45 has secured on its outer end a hand-wheel 12 or other suitable driver.

The drive-shaft 6 has loosely mounted thereon, facing each other and spaced apart, beveled segmental gears 13, both meshing with a beveled pinion 14, fixed upon a vertical driven shaft 15, supported in an elongated bearing 16 in base-plate 2, and this shaft 15 forms the dasher or agitator rod of a washing-machine.

Between segmental gears 13 and keyed to 60 slide on drive-shaft 6 is a clutch 17, having an annular cam-groove 18, into which the upper end of the driven shaft 15 projects, and inclined lugs 19 are located at each end of the clutch, and inclined sockets 20 of greater 65 width than the lugs are provided in the hubs of segmental gears 13 to receive said lugs 19 and alternately lock the segments to the drive-shaft.

The operation of my improvements is as 70 follows: The operating-shaft 10 is turned to continuously revolve drive-shaft 6 and drive-gear 7 in either direction through the medium of gear 9, meshing therewith. As drive-shaft 6 is revolved clutch 17 is also revolved, 75 and as its cam-groove 18 turns on the end of shaft 15 the clutch will be moved longitudinally to clutch with first one segmental gear 13 and then the other, and thus while one segmental gear acts as a driver the other is 80 an idler, and vice versa, thus alternately revolving pinion 14 and drive-shaft 15 in reverse directions.

Various changes might be made in the general form and arrangement of the parts described without departing from my invention, and hence I do not confine myself to the precise details set forth, but consider myself at liberty to make such changes and alterations as fairly fall within the spirit and scope 90 of my invention.

Having fully described my invention, what I claim as new, and desire to secure by Letters Patent, is—

The combination with a frame, having a 95 vertical bearing, and horizontal bearings, of a driven shaft mounted in the vertical bearing and having a rigid projection at its upper end, a driving-shaft mounted over the driven shaft, in said horizontal bearings, a gear on 100 the driven shaft, two gear-segments loose on the driving-shaft always meshing with the

gear on the driven shaft, and a clutch-sleeve rotatable with the driving-shaft and adapted to lock the gear-segments alternately thereto, said clutch-sleeve having a single cam-groove to receive the rigid projection on the driven shaft.

In testimony whereof I have signed this

specification in the presence of two subscribing witnesses.

JOHANN HOFMANN.
